DESIGN FOR A FRANKFURTER

Frank W. Trabold, Detroit, Mich.; Detroit Trust
Company and Irma J. F. Trabold, executors of Frank W. Trabold, deceased

Application October 15, 1938, Serial No. 80,473

Term of patent 14 years

To all whom it may concern:

Be it known that I, Frank W. Trabold, a citizen of the United States, residing in Detroit, in the county of Wayne, State of Michigan, have invented a new, original, and ornamental Design for a Frankfurter, of which the following is a specification, reference being had to the accompanying drawing, forming a part thereof, wherein:

Fig. 1 is a view in perspective of a frankfurter showing my new design.

Fig. 2 is a sectional view taken on the line 2—2 of Fig. 1, looking in the direction indicated by the arrows.

Both sides of the frankfurter are substantially identical in form and appearance.

I claim:

The ornamental design for a frankfurter, as shown and described.

FRANK W. TRABOLD.
